UNITED STATES PATENT OFFICE

171,477

TIE RACK

Reinhold J. Anderson, Red Oak, Iowa

Application July 6, 1953, Serial No. 25,800

Term of patent 14 years

(Cl. D80—9)

To all whom it may concern:

Be it known that I, Reinhold J. Anderson, a citizen of the United States of America, residing at Red Oak, in the county of Montgomery and State of Iowa, have invented a new, original, and ornamental Design for a Tie Rack, of which the following is a specification, reference being had to the accompanying drawing, forming a part thereof wherein:

Figure 1 is a perspective view of a tie rack, showing my new design;

Figure 2 is a view in side elevation of the same, and

Figure 3 is a top plan view of the same.

I claim:

The ornamental design for a tie rack, as shown.

REINHOLD J. ANDERSON.
